Primary Examiner — Mark A Goodwin*(74) Attorney, Agent, or Firm* — Taft Stettinius & Hollister LLP; Stephen F. Rost**CLAIM**

The ornamental design for an idler wheel weight, as shown and described.

DESCRIPTION

FIG. 1 is a side view of a drive track assembly with an idler wheel weight shown according to the present design; FIG. 2 is a front, perspective view of the idler wheel weight; FIG. 3. is a front view thereof; FIG. 4 is a rear view thereof;

FIG. 5 is a right side elevational view thereof;

FIG. 6 is a left side elevational view thereof;

FIG. 7 is a top plan view thereof; and,

FIG. 8 is a bottom plan view thereof.

The broken line representations in the figures show unclaimed environment or boundaries. The broken line representations thus form no part of the claimed design as filed.
